UNITED STATES PATENT OFFICE.

JOHN B. CHACE, OF ORANGE, MASSACHUSETTS.

WOODWORKING MACHINERY.

SPECIFICATION forming part of Letters Patent No. 603,037, dated April 26, 1898.

Application filed February 7, 1896. Serial No. 578,303. (No model.)

To all whom it may concern:

Be it known that I, JOHN BOYDEN CHACE, of Orange, in the county of Franklin and State of Massachusetts, have invented certain new and useful Improvements in Woodworking Machinery; and I hereby declare that the following is a full, clear, and exact description of the same, reference being had to the accompanying drawings, forming part of this specification.

This invention has reference to improvements in woodworking-machines, and especially in machines for cutting concave depressions in boards to serve as thumb-holes.

The object of the invention is to increase the accuracy of machines of this character and to render the same automatic in action.

The invention consists in the peculiar features of construction and combination of parts, as may hereinafter be described, and pointed out in the claims, whereby the object of the invention is accomplished.

Figure 1 represents a side elevation of the improved thumb-hole-cutting machine. Fig. 2 represents a plan view thereof. Fig. 3 represents a vertical longitudinal sectional view of the same. Fig. 4 represents a cross-sectional view. Fig. 5 represents an enlarged view of details of the cutter and the device for lifting and depressing the same. Fig. 6 represents a board illustrating the style of thumb-hole cut by this machine.

Similar numbers and letters of reference designate corresponding parts throughout.

The mechanism is supported on a framework consisting of the standards, as 8 and 9, the longitudinal brace 10, connecting the pairs of standards, and the base or top 11, mounted on the standard. Extending through a portion of the length of this top 11 is the slot 12, in which the feed-block 13 is reciprocal, the limit of the forward movement of this block being regulated by the set-screw 14, working through the depending portion 15 of the top 11.

On the top 11 is a hopper formed by the partitions or ends 16 and 17. The end 16 is stationary, having the lower feed-opening 18, governed at the center by the vertical adjustable bolt 19 and the webs 20 and 21. From

the web 21 and the adjoining portion of the end 16 extends the bearing-support 22. The end 17 is adjustable on the top 11 and is supplied with a clamping device 23, traveling in the groove 24 of the top. On the inner surface of this end are adjustably mounted the guides 25 55.

In the lower portions of the webs 20 and 21 is journaled the shaft 26, having the handle 27 and the oppositely-extending screw-threads 60 28 and 29, and on these threads are engaged the threaded sleeves 30 and 31, which are secured to the guide-arms 32 and 33, the vertical members 34 and 35 of these arms extending upward on the inner surface of the end 65 16. To these arms 32 and 33 are secured the downwardly-acting presser-springs 36 and 37. By the rotation of the shaft 26 the guide-arms 32 and 33, with their vertical members, are adjusted laterally to accommodate the particular width of boards which it is desired to 70 operate on.

The shaft 38 is journaled in the bearing of the support 22. On the outer end of this shaft 38 is the belt-pulley 39, having the slot 75 40 formed in a portion thereof. In this slot is adjustably secured the clamp 41, having a pivot on which the upper end of the connecting-rod 42 is journaled. The lower end of this rod is pivoted to the arm 43, extending 80 from the shaft 44, journaled in bearings projecting from the standards 8 8. From the central portion of this shaft 44 extends the lever-arm 45, the upper end of which is connected with the feed-block 13 by the rod 46, 85 pivoted at both ends.

The pulley 39 is driven by the belt 47, connecting the same with a pulley on the drive-shaft 48, which is journaled in bearings in the lower portion of the frame and also carries the band-wheel 49. At the lower portion of the machine is pivoted the lever 50, having the member 51, carrying the roller-bearing 52, by the pressure of which against the belt 47 the slack in the same is taken up. 95 When set to exert a desired tension on the belt, the lever 50 is held by the pawl 53 engaging one of the steps of the rack 54. At the sides of the top 11 are secured the brackets 55 55, between which is pivoted the frame 100

56. In this frame is journaled the cutter-shaft 57, having the band-pulley 58 at one end and the rotary cutter 59 and saw 60 at the other end. The free end of this frame has the 5 slotted member 61, in which the pivot-block 62 is adjustable by means of the set-screws 63. On this pivot is journaled the lower end of the link 64, the upper end of which is pivoted on the pin 65, set in the enlarged end of the shaft 38, off the axial center thereof. The bracket 55' has the stud 55², on which is rotatably mounted the angularly-disposed band-pulley 66, while on the bracket 67, extending from the top 11, is similarly mounted the pulley 68. The band 69 passes around the pulley-wheel 49 and thence over those pulleys 66 and 68 to the pulley 58 of the cutter-shaft to transmit rotary motion thereto.

The end 17 of the hopper is first placed a 20 suitable distance from the end 16 to accommodate the length of the boards A A. The guides 25 25 on the end 17 are next adjusted to the width of the boards. The handle 27 is now turned to rotate the shaft 26 to draw together or separate the guide-arms 32 and 33, the members 34 and 35 being at the same time adjusted within the hopper. The boards A A are now placed in the hopper between the members 34 and 35 at one end and between the guides 25 25 at the other end, and the bolt 19 is adjusted to allow for the 25 passage of but one board at a time through the opening 18. The mechanism is now started and through the driving-gear the pulley 39 and the shaft 38 is rotated. This causes the reciprocation of the feed-block 13, through the connections therewith. Passing through the opening in the lower portion of the end 17 the block engages the lowest of the pile of 30 boards and carries it along through the opening in the end 16 and between the guide-arms 32 and 33, where it is engaged and pressed downward by the spring-plates 36 and 37. This forward movement of the board continues until the block 13 is arrested by the stop-screw 14. During this operation the cutter-shaft has been rotated by its drive-band 69; but the cutter has been sufficiently raised to allow for the passage of the board. When the forward movement of the board ceases, the shaft 38 has been sufficiently rotated to bring the pin 65 past the vertical center. As this pin moves downward in its circular path the free end of the cutter-frame is also moved downward until the cutter 59 and saw 60 act to cut the thumb-hole B in the board A, the cutter forming the inclined concave recess, while the saw cuts the vertical wall forming the end of the hole. When this is accomplished, the cutter is raised by the rotation of the shaft 38 and the board is pushed out of the way by the next board which has been engaged by the feed-block after its return to its original position. Should the block 13 reach the stop 14 before the rotation of the pulley 39 has carried

the clamp 41 to its farthest forward point of circular movement, this pulley will be held from rotation by the stop, the block, and the connections between the block and the pulley, the tension on the belt 47 being regulated to allow for the slipping of the belt on the pulley. A spring-finger 16' is secured to the stationary end 16, extending outwardly therefrom, and has a bearing on the end of the board next to the thumb-hole cutter, thereby firmly holding the board to the bed of the machine during the cutting of the thumb-hole, as clearly shown in Fig. 3.

Should it be desirable to cut two thumb-holes in the board, one of the guide-arms 32 80 33 is adjusted on its sleeve 30 or 31, so that the board in passing under the thumb-hole cutter will be off the center and the thumb-hole will be cut to one side of the center. To cut the hole on the opposite side, the guide-arm first adjusted will be replaced to its central position on the sleeve and the other guide-arm will be adjusted so as to bring the thumb-hole cutter to that side of the center and the boards will be again passed through the machine, when the finished board will then have two thumb-holes, one to either side of the center.

Having thus described my invention, I claim as new and desire to secure by Letters Patent—

1. In a thumb-hole machine, the combination with the frame 56 pivotally mounted in the brackets 55 and 55', the cutter-shaft journaled longitudinally in the frame, and the cutters on the free end of the shaft, of the feeding device and connections intermediate the same and the frame 56, whereby the cutter-frame is raised at the operation of the feeding device.

2. The combination with the screw-threaded shaft 29, and the guide-arms 32 and 33 having bearings engaged with the screw-shaft and provided with the vertical ways 34 and 35 and the tension-springs 36 and 37, of the vibratory cutting device, as described.

3. In a thumb-hole machine, the combination with the cutter-shaft frame pivotally mounted and operated by the pulley 39 through the link 64, the cutter-shaft journaled longitudinally in the frame, a pulley on one end of said cutter-shaft and the cutter on the opposite end thereof, of the driving-pulley, the shaft on which the driving-pulley is mounted, the guide-pulleys, a belt working over the driving-pulley, the guide-pulleys and the pulley 58, and a belt working over the pulley 39 from the drive-shaft, substantially as and for the purpose herein shown and described.

4. In a thumb-hole machine, the combination of the following instrumentalities: the hopper provided with adjustable guides, the guide-arms provided with vertical members and presser-springs, the spring-finger 16', the

shaft 26 for adjusting the guide-arms 32 33, the pivoted frame 56, the cutter-shaft supported in the pivoted frame and provided with the pulley 58 at one end and the cutter at the 5 other end, the pulley 39 connected to the pivoted frame by the link, the reciprocal feed-block 13, and means, substantially as herein shown, for operating the pulleys 58 39 and

the reciprocal feed-block 13, as and for the purpose described.

In witness whereof I have hereunto set my hand.

JOHN B. CHACE.
